UNITED STATES PATENT OFFICE.

GEORGE N. MAS, OF LYNCHBURG, VIRGINIA.

DESIGN FOR A BOTTLE.

Application filed June 29, 1923. Serial No. 6,619. Term of patent 14 years.

To all whom it may concern:

Be it known that I, GEORGE N. MAS, a citizen of the United States, and a resident of the city of Lynchburg, county of Campbell, in the State of Virginia, have invented a certain new, original, and ornamental Design for a Bottle, of which the following is a specification.

Reference is made to the accompanying drawing which forms a part thereof.

The drawing is a perspective view of a bottle showing my new design.

I claim:

The ornamental design for a bottle as shown.

GEORGE N. MAS.

Witnesses:

KATHERINE McNAMARA,
VIRGINIA F. ANSPACH.
